EMBOSSING MACHINE

Harold O. Bates, Cranford, N. J.

Application April 17, 1940, Serial No. 330,052

12 Claims. (Cl. 197—6.4)

This invention relates to an embossing machine and more particularly to a device for embossing metal bands. The machine is particularly adapted for embossing small metal bands used as markers, as for example for small cylindrical objects like the legs of birds, pigeons, chickens, turkeys, animals, the tails of fish, cord, rope, wire or cable, tubes or the like.

It is an object of this invention to provide a device which will simply and neatly mark such bands with any insignia desired.

It is a further object to provide a machine in which the insignia can be changed at will or can be spelled out upon the band but at the same time the various characters will be neatly made and accurately spaced.

It is a further object to provide a device of the character described which will be of simple and rugged construction and easy to operate.

The invention accordingly comprises the features of construction, combination of elements, and arrangements of parts, which will be exemplified in the construction hereinafter set forth and the scope of the application of which will be indicated in the claims.

For a fuller understanding of the nature and objects of the invention, reference should be had to the following detailed description, taken in connection with the accompanying drawings, in which:

Fig. 1 is an end elevation of a machine embodying this invention.

Fig. 2 is a side elevation thereof.

Fig. 3 is a central longitudinal section viewed from the same position as Fig. 2.

Figs. 4, 5, 6 and 7 are details.

Fig. 8 is a sectional view of a modification.

The numeral 10 designates a frame carrying suitable ball bearings 11 in which is journaled a shaft 12. On one end of this shaft there is mounted a head 13, which is illustrated as shown in the form of a disc, carrying suitable dies 14, as will be later described. Pivoted to the frame 10 at 16 is a sub-frame 17 carrying ball bearings 18 in which is journaled a shaft 19 on one end of which is carried a head 20, here also shown in the form of a disc. The disc 20 is also provided with dies 21 corresponding to the dies 14 on the head 13.

As illustrated each die 14 comprises a stud 50 fitting into a hole 22 in the head parallel to the axis of the shaft 12 and each die is held in place by a set screw 23. The holes 22, and consequently the dies 14, thus extend outwardly from the face of the head 13 and are equally dis-

tant from the center of the shaft and equally spaced from each other around the circumference. Each die has upon its cylindrical surface at the point where it extends out beyond the disc, a male or female impression of the character which it represents. In order that the characters may extend outwardly away from the center of the band, I prefer to make the dies upon the studs 14 the male dies. These male impressions, therefore, are indicated by the number 24. Each of the dies 21 upon the head 20 is radially disposed upon the head and preferably held in place by a set screw 25 and each die 21 has a character upon it corresponding to the character upon the corresponding die 14 with which it is adapted to mate, and for the reasons already given, the characters upon the dies 21 are preferably of the female character. The studs 14 are of slightly smaller diameter than the inside of the ring to be operated on.

I prefer to make the face of the dies 21 cylindrically concave, the diameter of the cylinder being substantially the diameter of the band with which the device is to be used so that when the impression is made upon the band there will be no tendency to flatten the band at the point where it is engaged by the dies.

Each of the shafts 12 and 19 is provided at its other end with a gear 26—27 and an idler gear 28 is mounted upon the frame in a position to mesh with the gears 26 and 27 and thus to secure coordination of action between the heads 13 and 20.

The pivot 16 of the sub-frame 17 is preferably arranged close to and in line with the pitch diameters of the gears 27 and 28, so that as the sub-frame 17 is raised and lowered, as will hereafter be described, the gears 27 and 28 nevertheless remain in mesh.

It will be understood that each of the dies 21 is adapted to mate with one of the dies 14 and that the mating dies are so disposed around the periphery of their respective heads that as either head is rotated the mating dies will be brought into registry coordinately.

The sub-frame 17 is raised about its pivot 16 to free the heads for rotation and to permit the insertion of a band upon one of the dies 14 and the sub-frame is lowered about its pivot to bring the mating dies into embossing cooperation. To accomplish this result there is pivoted to the frame 10 at 30 a lever 31 which is connected to a link 32 which in turn is screw threaded as shown at 33 to a rod 34, which in turn is pivoted at 35 to a lever 36 operated by a foot treadle

37. A spring 38 connects the foot treadle with the frame 10, normally to hold the treadle 37 in raised position. The lever 31 is connected to the sub-frame 17 by a link 39 which is pivoted to the sub-frame at 40 and pivoted to the lever 31 at 41, the pivots being such that as the treadle 37 is depressed the lever 31 is drawn down and correspondingly the sub-frame 17 is lowered about its pivot 16 to cause the dies 21 to engage with the band and the dies 14. As soon, however, as the foot treadle is released, the spring 38 again raises the head 20.

The ratio of the operating levers will be chosen with regard to the size of the machine and the character of the work to be done.

The mechanism for supporting the bands which are to be embossed comprises a cross head 45 slidably mounted in guides 46 upon the frame and having a downwardly extending lug 47 carrying a pin 48. A lever 49 is pivoted to the frame at 50 and has at its upper end a slot 51 for engagement with the pin 48. The lower end of the lever 49 is pivoted at 52 to a link 53 which in turn is pivoted at 54 to a bell crank lever 55 pivoted to the frame at 56. The other arm 57 of the bell crank lever 55 is closely adjacent to the rod 34 and there is provided upon the rod a pair of blocks 58 and 59. The block 58 is of such size and is so located that when the rod 34 is moved downwardly by the depression of the foot treadle 31 the block 58 will engage the arm 57 of the bell crank lever 55 and rotate the same counterclockwise, as seen in Fig. 3, rotating the lever 49 counterclockwise and thrusting the cross head 45 to the left, as seen in Fig. 3, which motion, as will be hereafter described, brings one of the bands to be embossed over one of the dies 14 and in position to be engaged by one of the dies 21.

The other block 59 is of such position and shape that as the rod 34 is raised by the release of the foot treadle it will engage beneath the arm 57 and reverse the movement of the lever 49 and withdraw the cross head 45. With this construction it will be clear that during the first part of the downward movement of the sub-frame 17, that is during the first part of the downward movement of the rod 34, the lever 55, and consequently the cross head 45, completes its entire movement and thereafter as the rod 34 continues its downward movement the cross head 45 remains stationary by reason of the fact that the arm 57 is riding upon a cylindrical portion of the block 58. Correspondingly, during the reverse movement, the cross head 45 remains in position until after the upper head is raised sufficiently to free the band from the die 21. Lock nuts 60 are provided above and below the frame upon the rod 34 to limit the movement thereof in both directions.

The cross head 45 preferably takes the form of a block having a horizontal bore 61 therein adapted to receive an operating rod 62, which rod carries at its outer end a dividing head 63 operated by a handle 64, the dividing head itself being provided with a plurality of notches 65 in its periphery, adapted to cooperate with a pin 66 which is pressed upwardly against it by a spring 67, it being understood that the notches 65 correspond to the distances apart upon the band that it is desired to place successive characters.

The bore 61 is connected with a larger bore 68 with which it is concentric and in the bore 68 there is provided a spring chuck 69 having its outer fingers 70 constructed and arranged

(see Fig. 4) to grasp the end of one of the bands (see Fig. 5). In the form of chuck illustrated, the chuck itself has a conical surface 71 fitting within a conical surface 72 in the bore 68 and the chuck is attached to the rod 62. A spring 73 which may be partly carried in a bore 74 urges the rod 62 to the right and thus, by reason of the conical surfaces 71 and 72, closes the fingers 70 of the chuck. A removable pin 75 carried by the cross head 45 extends into a slot 76 in the chuck 69 to prevent the rotation of the chuck whenever for any purpose it is desired to unscrew the chuck from the operating rod 62. During normal operation the pin is not in place and is kept from being lost by a chain 77. A nut 78 holds the dividing head 63 in place upon the rod 62.

The bands with which this device is particularly intended to be used comprise usually small tubular aluminum or other metal or material sections, as shown in Fig. 5, having the ends rolled over as shown at 80 to form a bead. I find it convenient to grasp the band in the chuck by means of this rolled bead.

The operation of the device will be clear from the foregoing description.

Upon release of the foot treadle 37, the head 20 is raised and the cross head 45 is thrown outwardly. In this position one of the bands 80 may be inserted in the fingers 70 by pressing the head 64 against the action of the spring 73 to open the chuck. The cross head 20 may thereupon be rotated to bring into registering position the die representing the character to be embossed upon the band and this action correspondingly brings into registering position the mating die. Thereupon the foot treadle 37 may be depressed causing the cross head 45 to move inwardly inserting the band that it contains over the die 14 and this motion is completed before the head 20 completes its movement.

The continuing movement of the head 20 thereupon forces the die 21 into mating engagement with its corresponding die 14 through the aluminum, thus performing the embossed effect upon the aluminum band.

If it is desired to place more than one character upon the band, the treadle 37 may be released. The head 20 may then be rotated to bring the second character into position and the dividing head 63 may be turned one space and the foot treadle 37 may be again depressed. This operation will cause the second character to be embossed upon the band in spaced relation to the first one.

For the purpose of insuring the accurate registry of each die 21 with its corresponding die 14 and with the band, I prefer to provide means upon the cross head for engaging some portion of the head 20 to hold the head in accurate alignment during the embossing. This is preferably accomplished by providing a fork 81 which slides over the die 21 as the cross head is moved forward and engages both sides of the said die to hold it against lateral motion. It will be clear, therefore, that any engagement between the cross head 45 and any registerable point upon the cross head 20 would serve the same purpose.

In the modification illustrated in Fig. 8, there is mounted concentric with the disc 20 a rim 121 which may be attached thereto by screws 122. This rim 121 carries a dowel pin 123 extending outwardly from its rim adapted to enter a hole 124 in the periphery of the head 13, just before

the dies come together to insure complete registry of the dies.

The device is otherwise similar to that previously described.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A device for marking bands comprising a frame, a shaft journaled in said frame carrying a circular head, a plurality of dies mounted at circumferentially spaced points around said head, a sub-frame pivoted to said frame and having a second shaft journaled therein, a second circumferential head upon said second shaft, a plurality of dies carried by said second head at circumferentially spaced points, each adapted to mate with a corresponding die of said first mentioned head, a gear train connecting said shafts together, whereby mating dies will be brought simultaneously into registry as the shafts are rotated, said sub-frame being movable from a position to cause the registering dies to effect an embossing operation to a position to free said dies from each other, a chuck for holding a band to be marked, said chuck being slidable from a retracted position free from said dies to a forward position to present said band to the embossing dies and common means for moving said chuck forward and for tilting said sub-frame to bring said dies into operation.

2. A device in accordance with claim 1 in which the dies upon said first mentioned head are carried upon cylindrical studs of slightly less diameter than the interior of said band and said chuck is constructed and arranged to bring said band over a selected stud as said chuck is moved to forward position.

3. A device according to claim 1 in which the chuck is provided with means constructed and arranged to come into engagement with a die upon the movable head as said chuck is moved to forward position to insure that the mating dies will be in accurate alignment before the embossing pressure is applied.

4. A device in accordance with claim 1 in which said chuck is constructed and arranged to grasp a band by one end thereof and is rotatable, whereby the band may be rotated to present different circumferential portions of said band to the dies.

5. A device in accordance with claim 1 in which said chuck is constructed and arranged to grasp the band by one end thereof and is rotatable and is provided with a dividing head, whereby a band may be rotated to bring different equally spaced circumferential positions of said band to the dies.

6. A device in accordance with claim 1 in which

the dies upon the stationary head are carried upon cylindrical studs of substantially the diameter of the interior of the band and the dies upon the movable head are cylindrically concave of approximately the diameter of the band.

7. A device in accordance with claim 1 in which the dies upon the stationary head are carried upon cylindrical studs of substantially the diameter of the interior of the band and the dies upon the movable head are cylindrically concave of approximately the diameter of the band, the dies upon the stationary head extending outwardly from the face of the head approximately parallel to the axis of its shaft and the dies of the movable head extending radially outward therefrom.

8. A device for marking bands comprising a frame, a stationary die, a movable die adapted to cooperate therewith to emboss an article, a chuck for holding the article to be embossed, slidable from a retracted position to a position to present the article to the dies, means for moving the movable die into engagement with the stationary die including a vertically movable rod, a lever pivoted to said frame and connected to move said chuck from one position to the other and connections between said vertical rod and said lever for completing the movement of said chuck during the first portion of said movement of said vertical rod and for holding said chuck stationary during the remainder of the said movement.

9. A device for marking bands comprising a head carrying a plurality of dies, a movable head carrying a plurality of dies, each adapted to mate with one of the dies of said first mentioned head, said heads being rotatable to present any pair of mating dies in working position simultaneously, a chuck for holding a band to be marked and movable from a retracted position to a forward position to present said band to said mating dies, said dies on said stationary head being of substantially the same diameter as the interior of said band, whereby said band is held in position by any of said dies.

10. A device for marking bands comprising a head carrying a plurality of dies, a movable head carrying a plurality of dies, each adapted to mate with one of the dies of said first mentioned head, said heads being rotatable to present any pair of mating dies in working position simultaneously, a chuck for holding a band to be marked and movable from a retracted position to a forward position to present said band to said dies, said chuck being provided with a member constructed and arranged to engage the movable head as said chuck is brought into forward position to insure the accurate positioning of said mating dies.

11. A device in accordance with claim 10 in which said dies on said stationary head are of substantially the same diameter as the interior of said band, whereby said band is held in position by any of said dies.

12. A device in accordance with claim 1 having means upon said chuck constructed and arranged to engage the selected die of said movable head in the forward position of the chuck to hold said mating dies and band in alignment.

HAROLD O. BATES.
